UNITED STATES PATENT OFFICE.

THEOPHILUS VAN KANNEL, OF ROCKFORD, ILLINOIS.

LOCKING MEANS FOR DOORS OF ELEVATOR-SHAFTS.

SPECIFICATION forming part of Letters Patent No. 552,652, dated January 7, 1896.

Application filed August 29, 1895. Serial No. 560,859. (No model.)

To all whom it may concern:

Be it known that I, THEOPHILUS VAN KANNEL, a citizen of the United States, residing at Rockford, in the county of Winnebago and State of Illinois, have invented a new and useful Improvement in Locking Means for the Doors of Elevator-Shafts, of which the following is a specification.

The object of my invention is to provide the sliding doors at the different landings of an elevator-shaft with means moving with the elevator-cab and operating to lock each shaft-door and maintain it locked in its closed condition until the cab reaches the landing at such door, when the latter shall be unlocked and may be opened.

Referring to the accompanying drawings, Figure 1 is a view in sectional elevation, showing an elevator-shaft with shaft-doors at different landings equipped with my improved locking means, the cab being represented in the shaft by dotted lines; Fig. 2, an enlarged broken view, in section, of the threaded sectional rod carrying a locking-head, the section being taken at the line 2 on Fig. 1 and viewed in the direction of the arrow; Fig. 3, an enlarged broken view of the rod with a locking-head thereon shown in side elevation; and Fig. 4, a section taken at the line 4 on Fig. 1, viewed in the direction of the arrow and enlarged.

A denotes an elevator-shaft, and B B denote the sliding doors thereof, one provided at each landing, so that while only three of the doors are shown it is to be understood that the number thereof may correspond with the number of landings, and that my improved mechanism, hereinafter described, is to be arranged accordingly. On each door B, and projecting beyond the forward edge thereof, is a catch or finger r.

C is a rod supported to extend vertically in the shaft adjacent to the forward edges of the shaft-doors, and which I prefer to form in longitudinal sections connected by couplings t and threaded for some distance from their ends. This sectional construction of the rod avoids the necessity for threading it throughout. To support the rod, I suspend it from its upper end on a cable p passing about pulleys p' and p'', respectively provided at the upper end of the shaft A and outside the lat-

ter at the upper end of a side well A' extending parallel with the shaft, the cable extending downward in the well A' to and being connected with a shaft q of one of the drums D' and D'' of the hoisting mechanism D, that indicated being of a well-known hydraulic variety, about the drums of which the cables o, which carry the cab E, are wound in the usual manner.

For a purpose hereinafter described I prefer to provide a weight u' on the lower end of the rod C and to suspend on the cable p a greater weight u, from which I extend another length p' of the cable over a guide-pulley v to the drum-shaft q.

On the rod C are provided locking-heads F, one for each shaft-door. As shown, each head F is substantially in the form of a sector pivoted at one end on a pin n extending in suitable position relative to a door from the shaft-wall, the flaring end of the head being provided on one side with a flange m, divided by a slot m', and which should be concentric with the center n. Each head carries on a stem l', extending from one side, a sleeve l to surround the rod C and at which the head is adjustably fastened in place by means of nuts l'' engaging the threads on the rod to bear against the opposite ends of the sleeve l.

It will be noticed that the slots m' in the flanges m occupy different positions on the heads F, the arrangement being such that the extent of cable o wound upon or unwound from the drums D' D'' in the travel of the elevator-cab winds upon or unwinds from the shaft q such a length of the cable p as will lower or raise the rod C an extent to bring the slot in the flange m of the locking-head F for each shaft-door B coincident with the catch r on the door when the cab reaches the corresponding landing. Thus, as shown, the cab E is at the second landing, and the slot m' in the flange m on the head F at that landing coincides with the catch r on the corresponding shaft-door. If the cab descends to the lower landing the simultaneous lowering of the rod C will bring the slot in the flange of the lower locking-head coincident with the catch on the shaft-door at the lower landing and permit it to be opened, and the descent of the rod will accordingly turn the

head F of the middle landing on its pivot *n* sufficiently to carry the slot in its flange past the catch on the middle shaft-door, locking the latter against being opened, because the flange on that head is then presented to the catch instead of the slot. It will, therefore, be apparent that in the ascent or descent of the cab all the shaft-doors are locked until the cab reaches a landing, when the shaft-door at that landing is unlocked and may be opened.

I provide the weights *u'* and *u* to prevent breakage in the event that the locking-heads shall be obstructed in their operation. If the combined weight of the several locking-heads and the rod carrying them amounts to, say, fifty pounds and the weight *u'* be, say, twenty-five pounds, making a total of seventy-five pounds, the weight *u* should then be about one hundred pounds. The weight *u* is lifted by the winding mechanism, causing the rod C to descend, and the reverse motion allows the weight *u* to act to overcome the aggregate weight of seventy-five pounds referred to on the rod, which will then rise.

If the cable *p*, which is moved by the hoisting mechanism, were attached directly to the cable *p*, and any of the locking-heads or other parts should become fouled, something would break, whereas by my improved arrangement the entire power applied is no greater than the difference between the two weights.

While the particular construction of my improved safety-lock mechanism for elevator-shaft doors is the best known to me for the purpose, it may be variously modified as to details without departure from my invention. Hence I do not limit my invention to the exact details shown and described, except where particularly set forth in the appended claims.

What I claim as new, and desire to secure by Letters Patent, is—

1. In combination with the doors of an elevator-shaft and the cab and its hoisting mechanism, catches on the doors, and locking-heads suspended in the shaft to normally engage said catches to lock the doors and connected with the hoisting mechanism to be raised and lowered with the movements of the cab, proportionately thereto, to unlock the catch on each door when the cab reaches the landing corresponding therewith, substantially as described.

2. In combination with the doors of an elevator-shaft and the cab and its hoisting mechanism, catches on the doors, a rod suspended in the shaft by a cable connected with the hoisting mechanism, to cause the rod to be raised and lowered with the movements of the cab, proportionately thereto, and locking-heads pivoted in the shaft and confined on the rod in positions to normally engage said cables to lock the doors, whereby the ascent and descent of the rod with the movements of

the cab unlock the catch on each door when the cab reaches the landing corresponding therewith, substantially as described.

3. In combination with the doors of an elevator-shaft and the cab and its hoisting mechanism, catches on the doors, a rod suspended in the shaft by a cable connected with the hoisting mechanism to cause the rod to be raised and lowered with the movements of the cab, proportionately thereto, and locking-heads pivoted in the shaft and adjustably confined on the rod in positions to normally engage said catches to lock the doors, whereby the ascent and descent of the rod with the movements of the cab unlock the catch on each door when the cab reaches the landing corresponding therewith, substantially as described.

4. In combination with the doors of an elevator-shaft and the cab and its hoisting mechanism, catches on the doors, a rod C suspended in the shaft by a cable connected with the hoisting mechanism to cause the rod to be raised and lowered with the movements of the cab, proportionately thereto, and locking-heads F provided at their free ends with flanges *m* having slots *m'* and pivoted at their opposite ends and confined on the rod in positions to normally engage, at their flanges, the said catches to lock the doors, whereby the ascent and descent of the rod with the movements of the cab turn the heads on their pivots to bring the slot in a head coincident with the catch on a door when the cab reaches the landing corresponding therewith, substantially as described.

5. In combination with the doors of an elevator-shaft and the cab and its hoisting mechanism, catches *r* on the doors, a rod C suspended in the shaft by a cable connected with the hoisting mechanism to cause the rod to be raised and lowered with the movements of the cab, proportionately thereto, and locking-heads F provided at their free ends with flanges *m* having slots *m'* and pivoted at their opposite ends and provided with sleeves *l* at which they are confined on the rod in positions to normally engage, at their flanges, the said catches to lock the doors, whereby the ascent and descent of the rod with the movements of the cab turn the heads on their pivots to bring the slot in a head coincident with the catch on a door when the cab reaches the landing corresponding therewith, substantially as described.

6. In combination with the doors of an elevator-shaft and the cab and its hoisting mechanism D, catches *r* on the doors, a rod C suspended in the shaft by a cable connected with the shaft *q* of said hoisting mechanism to cause the rod to be raised and lowered with the movements of the cab, proportionately thereto, and locking-heads F provided at their free ends with flanges *m* having slots *m'* and pivoted at their opposite ends and confined on the rod in positions to normally engage, at their flanges, the said catches to lock the doors,

whereby the ascent and descent of the rod with the movements of the cab turn the heads on their pivots to bring the slot in a head coincident with the catch on a door when the cab reaches the landing corresponding therewith, substantially as described.

7. In combination with the doors of an elevator-shaft and the cab and its hoisting mechanism, catches on the doors, a rod suspended in the shaft by a cable p , a weight w on said cable and connected by a cable p' with the shaft q of said hoisting mechanism, a weight

w' on the rod, and locking-heads F pivoted in the shaft and confined on the rod in positions to normally engage said catches to lock the doors and to unlock the catch on a door when the cab, in its movements, reaches the landing corresponding therewith, the whole being constructed and arranged to operate substantially as described.

THEOPHILUS VAN KANNEL.
